UNITED STATES PATENT OFFICE.

HENRY C. WOLF, OF CATAWISSA, PENNSYLVANIA.

WINDOW-SCREEN.

1,099,003.

Specification of Letters Patent.

Patented June 2, 1914.

Application filed May 1, 1913. Serial No. 764,906.

To all whom it may concern:

Be it known that I, HENRY C. WOLF, a citizen of the United States, residing at Catawissa, in the county of Columbia and State of Pennsylvania, have invented new and useful Improvements in Window-Screens, of which the following is a specification.

This invention relates to improvements in window screens and particularly to the adjustable type, and the primary object of the invention is to provide a screen mounting or organization which is adapted to be held at any desired location opposite either the upper or the lower portion of the window frame or the upper and lower sash, the screen being guided and held by yielding vertical rods with their lower extremities free or unattached and of less length than the vertical extent of the inside portion of the window frame and permitting the screen to be readily applied or detached. The screen is also constructed with means for adjusting the same relatively to the width of the inner portion of the window frame and specifically comprises slidable sections with coöperating spring means acting to normally distend the sections and set up a frictional engagement of the outer side edges of the sections with the inner opposite side portions of the window frame.

The invention consists of the construction and arrangement of parts which will be more fully hereinafter described and claimed.

In the drawing: Figure 1 is an elevation of a window frame and sash showing the improved screen organization applied thereto and broken away in part. Fig. 2 is a transverse vertical section on the line 2—2, Fig. 1, showing a portion of the organization in section. Fig. 3 is an enlarged detail horizontal section on the line 3—3, Fig. 1.

The numeral 5 designates a window frame of usual construction having lower and upper sash 6 and 7 respectively movable in grooves 8 and 9 separated by a parting bead 10. To the inner portion of the top of the frame and beyond the plane of movement of the inner or lower sash 6, resilient guide rods 11 are secured and depend inside the frame to about the distance shown particularly by Fig. 1, the lower extremities of the said rods 11 being free or unattached. It will be understood that the rods 11 may be disposed any distance apart or will be arranged proportionately to the width of the opening

of the window frame and they may also be lengthened or shortened in accordance with the vertical extent of the said opening. The rods 11 may also be of any suitable gage 60 and will be preferably of a non-corrosive nature.

The screen is composed of two sections 12 and 13 which are slidably associated through the medium of slides 14 so that one section may be moved over upon or outwardly over the other section to accommodate variations in width of the openings of different window frames. The sections 12 and 13 have the opposite extremities of an expansion spring 70 15 in engagement therewith, the inner end of said spring being secured to the section 12 and the outer end curved as at 16. Along the outer end portions of the screen sections 12 and 13, tubular guides 17 and 18 are 75 mounted and are fully open at their opposite ends, said guides being preferably of metal, and as shown by Fig. 3 may be formed integral with the end strips 18 of the sections 12 and 13 to simplify the construction and 80 avoid the use of extra pieces for the construction of the said tubular guides. The outer curved end 16 of the spring 15 extends into a slot 19 of the tubular guide 17 and bears against the rod 11 engaging said 85 guide, as clearly shown by Fig. 3, and operates to a certain extent to set up a frictional tension between the rod 11 and the guide 17. The primary purpose of the spring 15, however, is to maintain the sections 90 12 and 13 in laterally distended association so as to cause the outer side edges of the said sections to frictionally bear with such pressure against the side portions of the window frame engaged thereby as to 95 prevent too loose movement of the screen as a whole and prevent the latter from slipping under certain conditions and also to form closed joints between the opposite side edges of the screen sections and the side portions 100 of the window frame.

The screen is freely adjustable to dispose the same either at the lower portion of the window frame, as shown by Fig. 2, or at the upper portion of said frame. When the 105 screen is at the lower portion of the window frame and the lower sash 6 is raised, the top of the screen may be pushed under the bottom rail of the lower sash, as shown by Fig. 2, owing to the yielding nature of the rods 110 11 and thus be held against movement or loose displacement. The screen may be re-

leased from the sash 6, as shown by Fig. 2, and said sash lowered and the outer sash also lowered and the screen pushed upwardly to cover the open space formed by 5 the depression or lowered disposition of the upper sash, and in this position the screen may have its lower portion engaged by the top rail of the lower sash to hold the said screen against loose movement and provide 10 a tight joint between the same and the lower sash. The yielding nature of the rods 11 and likewise the collapsible association of the sections 12 and 13 of the screen permit the latter to be readily detached from the 15 rods desired and subsequently mounted in operative position in connection with the rods. The latter operation may also be readily accomplished in view of the fact that the lower extremities of the rods are loose 20 or unattached and do not extend fully to the lower or sill portion of the window frame.

It is proposed to make the screen of non-corrosive material and to construct the several parts thereof to the best advantage from 25 a standpoint of economy in manufacture and without in the least detracting from the strength and durability of the same. The improved screen organization will be found exceptionally convenient and it will be observed that the same may be applied in operative position simply by securing the rods 11 to the window frame as hereinbefore explained and then associating the screen proper therewith. This manner of mounting 35 the screen in connection with a window frame avoids the necessity of applying extra bead strips or other attachments on opposite sides of the window frame and also permits the screen to be raised to clear the lower sash 40 or lower open portion of the window frame without detaching the screen as in ordinary screen applications, and in addition the upper or lower portion of the window frame may be covered by the screen as may be desired 45 and thus permit either the upper or lower sash to be opened for ventilation or other purposes without liability of entrance of insects and without requiring the use of

separate screens for the upper and lower portions of the window frame. 50

What is claimed is:

1. The combination with a window frame and a sash, of yielding rods secured to the upper portion of the frame and depending between the sides of said frame, the lower 55 extremities of the rods being loose, and a screen having means at opposite sides thereof slidably engaging the said rods and also compressible under a portion of the sash.

2. The combination with a window frame 60 and a sash, of yielding rods secured to the upper portion of the frame and loosely depending between the sides of said frame, and a screen having means slidably engaging the said rods and also compressible under 65 a portion of the sash.

3. The combination with a window frame and a sash, of yielding rods secured to the upper portion of the frame and loosely depending between the sides of the frame, and a screen having guide tubes at opposite sides 70 through which the said rods are freely movable.

4. The combination with a window frame and a sash, of yielding means depending 75 from the upper portion of the frame and loosely depending between the sides of the frame, and a screen adjustably engaging the said means and compressible outwardly for engagement by a portion of the sash and 80 operative to close either the lower sash opening or the upper sash opening.

5. The combination with a window frame and sash, of yielding means depending from the upper portion of the frame and having 85 loose lower extremities, and a screen slidably engaging the said yielding means and comprising adjustable sections engaged by a spring to hold the same distended.

In testimony whereof I have hereunto set 90 my hand in presence of two subscribing witnesses.

HENRY C. WOLF.
